SHOE

Samuel Wolff, St. Louis, Mo., assignor to Wolff-
Tober Shoe Mfg. Company, St. Louis, Mo., a
corporation of Missouri

Application July 10, 1931. Serial No. 549,846

3 Claims. (Cl. 36—76)

This invention relates to a certain new and useful improvement in shoes.

My invention pertains more particularly to the manufacture of feminine foot-wear of the so-called "glued" or cemented type of construction, in which more especially the prevailing mode or fashion provides a last having an instep relatively very narrow in width.

In the manufacture of a shoe of the character described, the usual metallic shank-reinforcing piece or stiffener is mounted on the instep of the shoe between the pulled-edges of the upper and the outsole or, alternatively, between the upper and the insole of the shoe. As at present constructed, however, the presence of the metal shank-stiffener interrupts the gluing surface at the instep of the shoe, and hence the adhesive connection there provided becomes insufficient for most efficiently and effectively securing the several parts together, the zone of weakness residing between the insole and the upper or the upper and the outsole according to the location of the shank-stiffener in the shoe.

Inasmuch as it is also requisite that the shank-stiffener be firmly secured against displacement on the relatively narrow instep of the shoe, it has been heretofore customary, so far as I am aware, to tack or nail the shank-stiffener to the insole of the shoe. In practice, however, the employment of metallic fasteners as tacks and nails gives rises to bumps and ridges in, and more especially at, the front of the instep of the shoe, due to the comparatively light and thin-walled construction of the shoe as manufactured for feminine wear, such bumps and ridges hence occurring where the flexing of the shoe-sole is in use most pronounced, with consequent objectionably rapid destruction of the fabric of the stocking of the wearer.

My invention has hence for its chief objects the provision in a shoe-structure of a novel form of insole incorporating means devoid of nails or like fastenings for retaining the shank-stiffener firmly in position and, at the same time, providing an uninterrupted gluing surface for fully adhesively securing and correspondingly strengthening the attachment of the pulled-edges of the upper in outsole-receptive position on the instep of the shoe.

My invention has for still another object the provision of a manufactured shoe incorporating a reinforced-shank construction, wherein the shank-reinforcement is retained securely against displacement in the shoe by means devoid of nails, tacks, or the like, thereby promoting the personal

satisfaction and comfort of the user of the shoe.

And with the above and other objects in view, my invention resides in novel features of form, construction, arrangement, and combination of parts hereinafter described and pointed out in the claims.

In the accompanying drawing,—

Figure 1 is a bottom plan view of the insole of a shoe constructed in accordance with and embodying my invention;

Figure 2 is a longitudinal sectional view of the insole taken approximately along the line 2—2, Figure 1;

Figure 3 is a bottom plan view of a shoe in process of manufacture according to my invention, the insole being shown in place and the upper having been pulled and secured thereon;

Figure 4 is a view similar to Figure 3, showing the shank-stiffener inserted between the insole and its pocket-forming member;

Figure 5 is a bottom plan view of a completed shoe manufactured according to my invention; and

Figure 6 is a perspective view of a common or standard form of shank-stiffener suitable for use in connection with my invention.

Referring now more in detail and by reference characters to the drawing, A designates the insole, which comprises a body-member 1 of suitable material, as relatively thin, flexible leather, composition, or the like, fashioned and formed suitably for its intended purpose, as well known to those skilled in the art.

Attached to and upon the outer face of the insole-body 1 preferably by means of a suitable adhesive 2, such as rubber-cement or the like, which remains viscous when in use, is a shank-pocket providing member 3 comprising a strap or section of preferably merely slightly pliable material, as card- or fiber-board or the like, which is of a length to extend from the fore-end of the shank 4 most conveniently also in insole-stiffening manner rearwardly to and over the heel-portion 5 of the insole-body 1.

Medially in its forward margin, the member 3 is provided with a preferably V-shaped notch 6 for facilitating the endwise insertion, in presently-appearing pocket-like accommodation between the member 3 and the insole-body 1, of a shank-stiffener B, which comprises a suitably elongated bar of preferably metallic-material having a suitably arch-wise conformation for residing neatly in the instep of the finished shoe, one form of such shank-stiffener being clearly illustrated in Figure 6.

In the manufacture of a shoe according to my invention, the insole A, constructed as described, that is to say, equipped with the pocket-providing section 3, is mounted on the customary last, 6 and the upper C stretched thereupon and its marginal portions, as at c, snugly pulled upon and over the outer face of the insole A and its attached section 3 and thereto adhesively and otherwise fixed and secured in the customary 10 manner well known to those skilled in the art, as best seen in Figure 3. It will be observed that the presence of the member 3 permits the subsequent insertion and placement of the stiffener B at its desired location, while at the same time, 15 the member 3 provides for a smooth flat contact of the marginal portions c of the upper C with the insole A especially at and with the instep of the shoe where the extremely narrow width of the shank necessitates the meeting engagement 20 of the opposite edges of the upper, in order that the gluing area may be adequate for securing the upper to the insole.

The upper-pulling and gluing operations being completed, as illustrated in Figure 3, and the upper C being hence now fully secured to the insole A, the stiffener B may with the greatest ease, convenience, and facility be needed, so to speak, under the member 3 for location neatly and precisely in the arch of the instep, as seen, in 30 Figure 4.

The adhesive-body 2 by reason of its viscous nature is adapted for yielding readily in pocket-providing manner for accommodation of the shank-stiffener B between the insole-body 1 35 and its adhering pocket-member 3, the shank-stiffener B being retained adhesively in its inserted insole-accommodated position by reason of the clinging nature of the rubber-cement preferably employed for the purpose.

40 Thereafter the out-sole D and the heel E may be mounted on the shoe-assembly in the usual manner, as shown in Figure 5, and it will be further observed that, notwithstanding the relatively very narrow width of the shank 7 of the 45 out-sole D, the stiffener B is fully protected from displacement in the shoe-structure by reason of the enclosure afforded by the member 3 of the insole A.

Thus, in a simple and efficient manner, I attain the objects stated and enable the economical and facile production of neat and comfortable fitting, attractive, and durable footwear of especially the so-called cemented type.

It will be understood that changes and modifications in the form, construction, arrangement, and combination of the several parts of the shoe may be made and substituted for those herein shown and described without departing from the nature and principle of my invention. 80

Having thus described my invention, what I claim and desire to secure by Letters Patent is,—

1. In a shoe-insole, a main flexible material-section having a shoe conforming shape and contour, a pliable material section disposed flatwise upon the outer face, and having a shape and contour to extend from the fore-end of the shank rearwardly to and over the heel-portion, of the main section, and an adhesive which remains viscous when in use disposed between said sections for securing the second section to and upon the outer face of the main section in the formation therewith of a shank stiffener pocket yielding to the insertion of a shank stiffener which is adhesively and permanently retained therein. 85

2. A shoe-insole including a main flexible material-section having a shoe conforming shape and contour, a pliable material section disposed flatwise upon the outer face, and having a shape and contour to extend from the fore-end of the shank rearwardly to and over the heel-portion, of the main section, an adhesive which remains viscous when in use disposed between said sections for securing the second section to and upon the outer face of the main section in the formation therewith of a pocket, and a shank stiffener disposed and by said adhesive permanently retained in said pocket. 95

3. A cemented shoe including a flexible insole having a shoe-conforming shape and contour, a pliable material section disposed flatwise upon the outer face, and having a shape and contour to extend from the fore-end of the shank rearwardly to and over the heel-portion, of the insole, an adhesive which remains viscous when in use disposed between the insole and said section for securing said section to the insole in the formation of a pocket having an adhesively closed opening, a shank stiffener disposed and by said adhesive permanently retained in said pocket, and an upper having its marginal portions folded over and cemented to and upon the combined outer face of the insole and said section. 110
